[57] **CLAIM**

The ornamental design for a display holder for teeth, as shown and described.

DESCRIPTION

FIG. 1 is a diagrammatic perspective view of the display holder for teeth, shown in the open position.

FIG. 2 is a diagrammatic perspective view of the display holder for teeth, shown in the closed position.

FIG. 3 is a rear elevational view of the display holder for teeth in the closed position.

FIG. 4 is a left side elevational view thereof.

FIG. 5 is a right side elevational view thereof; and,

FIG. 6 is top plan view of the display holder for teeth in the closed position, the bottom plan view being a mirror image of the top view.
